UNITED STATES PATENT OFFICE.

EDGAR R. MCCLURE, OF LOS ANGELES, CALIFORNIA.

MILK-COOLER.

1,086,302.

Specification of Letters Patent. Patented Feb. 3, 1914.

Application filed August 19, 1912. Serial No. 715,740.

To all whom it may concern:

Be it known that I, EDGAR R. MCCLURE, a citizen of the United States, residing at Los Angeles, in the county of Los Angeles and State of California, have invented a new and useful Improvement in Milk-Coolers, of which the following is a specification.

This invention relates particularly to devices for preparing milk for domestic use, and its principal object is to provide a cooler to combine the features of cooling and also adapted to have its function changed to a sterilizer.

It is also an object to provide a cooler that may be cooled either by the use of ice or fluid cooling solutions.

It is also an object to provide the cooling tubes of such a cooler provided with spreaders which will compel the fluid to contact 20 with the cooling surface in a film.

It is a further object to provide means for readily cleansing the tubes from a point outside the cooling compartment.

In the drawings accompanying this specification Figure 1 is an elevation in section showing the ice chamber and the cooling chamber, a portion of the outer side walls being shown in elevation. Fig. 2 is an end view of the apparatus, a portion of the end wall being broken away in three places to clearly show the tubes and hopper in which the tubes empty. Fig. 3 is a plan view, partly in section, to clearly show the housing around the hoppers. Fig. 4 is a detail perspective of a portion of one of the cooling tubes showing the method of securing a spreader inside the tube.

More specifically in the drawings like numerals indicate the same parts in the different views, 5 designating the side walls of the compartments, and 6 the end walls, preferably built of metal with a heat non-conductive lining, or of wood as shown in the drawing. The top of the casing 7 is provided with a hinged door 8 which provides an opening into the ice chamber 9, this being separated from the main cooling chamber 10 by the perforated floor 11 shown as built of heavy wire fabric.

Chamber 10 is below chamber 9 being provided with a removable bottom 12, with the short walls 13 provided with flanges 14 which engage with similar flanges 15 on the side and end walls above described, being 55 securely held by the bolts 16 or other fastenings. This receptacle bottom contains with-

in it the agitator 17 shown as a spiral screw mounted on the shaft 18, journaled in the short walls 13, the outer end of the shaft being provided with a pulley 19 to be driven by any suitable source of power when desired. This receptacle bottom also supports the steam pipe 20 provided with perforations which admit steam to the chamber 10 when desired, the valve 21 controlling the source of supply from some suitable boiler. A drain cock 22 is also tapped into the bottom 12 to provide means for withdrawing fluids accumulated or introduced into the chamber 10. The overflow pipe 23 is also provided, extending from the top of the chamber and leading out through the bottom 12, the valve 24 controlling this overflow pipe, the valve being located preferably just below the bottom 12. Auxiliary housings 25 or closures are formed on the end walls by a continuation of the side walls 5 and closed by the tops 25 and the bottoms 26 and the doors 27, one of these housings being duplicated on each end wall to provide inclosures 28 for the hoppers 29.

Extending into the top 25 of the housing on one side is a pipe 29 leading from the reservoir 30 to convey fluid to the hopper immediately under the pipe and affording communication to the lower end of the tube 31. This tube as clearly shown, is inclined so that the fluid will entirely cover its entrance orifice before it makes its exit at its other end, these ends being mounted in the end walls 6 of the main casing. From this exit orifice in the tube, the fluid drops to the first hopper thereunder communicating with the tube 32, this tube also extending across the chamber 10 and inclined in the reverse direction where it empties outside the end wall 6 of the chamber into the next hopper 28. A series of these tubes form a circuitous passage, and a plurality of them are shown mounted in the same relative vertical plane, a pair of tubes being preferably placed on either side of the overflow pipe 23 which adjoins the ammonia supply pipe 33 controlled by the valve 34. The hoppers 28 are preferably formed of sheet metal as shown, each hopper having at its most dependent portion an aperture formed therein adapted to be closed by the plugs 35, these plugs 35 being normally in position to close the orifice and withdrawn when it is desired to clean the structure. Within the tubes 31 and 32 are preferably mounted the spreaders 36 and 37.

ers 36 in concentric relation with the inner periphery of the tube, by the spacers 37, these spreaders being preferably formed of tubing with the closed ends 38. The lower-
 5 most of the cooling tubes 32 is provided with an exit trough 40 leading the milk to any suitable container outside the casing and the housing. In the operation of this device when it is desired to cool a fluid, as milk,
 10 ice may be introduced into the chamber and the supply in reservoir 30 is allowed to flow through by a suitable controlling means not shown until a desired temperature is reached at the exit 40. If ice is not at hand,
 15 a brine solution of common salt and water may be introduced in the chamber 10 and the brine kept in solution by means of the agitator 17. Ammonia coils 33 are also provided so that this cooling medium may be
 20 allowed to enter the coils and produce the cooling effect whenever needed. When it is desired to use the device as a sterilizer, water is introduced in the chamber 10, live steam injected therein through the pipe 20 resulting
 25 in a pasteurization of the milk, or the steam alone may be used if desired. When it is desired to clean the device, the doors 27 may be removed and the water directly injected into the upper ends of the cooling
 30 tubes, the plugs 35 are removed which permits the water to drop into the hopper next below and be readily carried away. The spreaders 36 may be built removable so that they can be readily withdrawn when it is
 35 desired to clean the structure. The parts

supported by the bottom 12 are also easily removed by detaching the bolts 16. Suitable clips 42 are provided to hold the doors 27 securely in position.

What I claim is:

1. A milk cooler, comprising a receptacle adapted to contain a cooling medium, a plurality of inclined tubes supported therein and extending across the same and hoppers mounted external to the receptacle, forming communication between said tubes, the lower portions of the tubes extending to the lower portion of said hoppers, and the tops of said hoppers extending above the level of the oppositely disposed ends of the tubes to that communicating with said lower portion of the hoppers.

2. A milk cooler, comprising a casing having an upper and a lower compartment communicating with one another, a series of inclined tubes mounted in the walls of said lower compartment and extending across the lower compartment reversely inclined to the flow of the liquid therein, hoppers forming reservoirs in connection with said inclined pipes provided with apertures, and removable means for spreading the liquid circulating in said tube.

In witness that I claim the foregoing I have hereunto subscribed my name this 12th day of August, 1912.

EDGAR R. McCLURE.
